UNITED STATES PATENT OFFICE

CHARLES F. JANSSEN, OF ASTORIA, NEW YORK

TACKLE BLOCK

Application filed May 16, 1931. Serial No. 537,849.

This invention relates to hoisting devices of the block and tackle type in general, and particularly to the kind known as self-locking in which a cord, cable, rope or the like is permitted to unrestrictedly move or travel in one direction, while it is automatically gripped and firmly held when its motion is reversed, and which grip hold may be instantly released through a slight pull upon the gripping provisions.

The prime object of my invention resides in providing in connection with a hoisting device of this kind employing cord, rope or the like an automatically operable and manually releasable rope gripping device which is so constructed as to normally have the tendency of positively engaging the rope while the latter is either in motion in one direction, or at standstill, and to actually grip and hold the rope or the like against movement, when the motion of the rope is reversed.

Another object of my invention is to provide in connection with a hoisting device of this kind a block with specially designed cheeks adapted to engage the outer surfaces of a rope or cable, and a rope or cable brake centrally disposed between the cheeks and the inner surfaces of the cable for locking the latter in place.

A still further object of my invention is to provide with said cable brake a releasing lever, operable manually from without the block cheeks, and provided with spring controlled means for keeping the lever, and thereby the cable brake in a position at which the latter will always engage, or have the tendency to engage the inner surfaces of the cable.

The foregoing and still further objects of my invention will become more fully apparent from the following description, and the accompanying drawings, forming part of this specification, and in which:

Fig. 1 is an end elevation of my hoisting device, constructed as at present preferred.

Fig. 2 is a side elevation thereof.

Fig. 3 is a front elevation of an enlarged detail view of my tackle block.

Fig. 4 is a side elevation thereof, partially

in section, showing my rope arresting device in operative position.

Fig. 5 is a similar partial side elevation of the block, with the rope arresting means in rope engaging position.

Fig. 6 is a top view of the block, with the cable arresting device in plan view.

Referring now specifically to Figs. 1 and 2, numeral 10 is conventional, double pulley tackle block, to which is attached by means of cable, thimble 11 of cable or rope 12. Below block 10 is arranged a double pulley tackle block 13 of my special construction, which consists of cheek members 14, pointed at their lower ends, while their upper ends are widened up.

On observing Fig. 2, it will be seen that the left hand upper corner 15 is somewhat lower than the left hand upper corner 16 of the cheeks. A conventional strap 17 passes about the cheeks and provides suspension means for hook 18.

The arrangement of my cable locking device may be best understood from Figs. 3, 4, 5 and 6, where sheave pin 19 is shown passing through strap 17 which extends above the sheaves to the upper center of the cheek members 14, where another pin 20 is secured.

Between the cheek members, and disposed at the lower corner 15 and the upper corner 16 thereof, are spacers 21 and 22 respectively, which are arranged at different levels. They are held in position by rivets or other suitable means and their inner surfaces are hollowed out as clearly seen in Fig. 6, at 23 for normally accommodating a rope or cable, and for facilitating its gripping, as will be explained presently.

Pivots mounted upon upper pin 20, between cheek members 14 is my cable arresting device which comprises a hub 24 which extends at both ends and supports both sides jaws or gripping members 25 provided with hollowed-out engaging faces 26, adapted to grip the inner surfaces of the cables. From the center of hub 24 extends over the lower spacer 21 an operating lever 27, equipped with a pull rope engaging eye 28 and provided with a spring controlled pin 29, intended to bear against spacer 21 and normally push

lever 27 into upward position, thereby causing the jaws of gripping members 25 to be steadily in a so to speak dragging engagement with the cable strands.

5 Pin 29 may be adjusted by means of a screw cap 30, whereby the tension of the spring bearing against the pin may be regulated.

10 Associated with eye 28 of lever 27 is a pull rope 31, which, when operated, causes lever 27 to swing downwards, as shown in Fig. 4, whereby the jaws of cable gripping members 25 are brought out of engagement with and into cleared position relative to the cable portions.

15 When pull rope 31 is released, and when the movement of the cable is reversed to that at which a load is hoisted by the device, gripping members 25 will immediately wedge the cable portions against stationary gripping or spacer members 22, as illustrated in Fig. 5, and lever 27 will swing upwards. The function of my device is automatic and prevents back-slipping of the cables during hoisting operation, or when the such operation is temporarily stopped.

20 Reverting again to Fig. 1, I have shown that the cable extends from thimble 11 downwards, passes over left hand sheave of the lower block, then upwards to and over the left hand sheave of the upper block, then downwards again and over the right hand sheave of the lower block, and up and over the right hand sheave of the upper block. From that sheave the cable extends outwards and forms the engaging or operating end 32.

25 One of the outstanding advantages of my arrangement resides in its safety. Assuming that the cable breaks at any point, the gripping members 25 will immediately function and engage the cable portions remaining in the lower block and lock them against further movement, thereby preventing the load from falling and causing damage or injury to the operator.

30 While I have shown a specific form of my double sheave device, triple, quadruple sheave blocks, and other changes and improvements may be readily incorporated, and I therefore reserve for myself the right to make such changes and improvement within the broad scope of my invention, as set forth in the annexed claim.

35 I claim:

40 In a multiple sheave block, a pair of cheek members, a plurality of stationary cable engaging spacers, a plurality of pivotally mounted cable gripping members operatively located between said spacers and forming one movable unit, a releasing arm extending from the unit, a spring controlled member slidably in a recess in said arm and bearing against one of said spacers and adapted to normally elevate said arm, thereby keeping said cable gripping members normally in light engage-

ment with a cable passing through the block without affecting the usual operation of such cable while it moves in one direction during the hoisting of a load, said gripping members adapted to firmly engage and press such cable against said spacer when such cable either breaks or moves in oppositely to the aforementioned direction.

45 Signed at New York, in the county and State of New York, this 15th day of May, 75 1931.

CHARLES F. JANSSEN.
